UNITED STATES PATENT OFFICE.

HASCAL A. HOGEL, OF NEW YORK, N. Y.

ROASTING-FURNACE.

No. 926,942.

Specification of Letters Patent.

Patented July 6, 1909.

Application filed July 27, 1905. Serial No. 271,468.

To all whom it may concern:

Be it known that I, HASCAL A. HOGEL, a citizen of the United States, residing at New York, in the county of New York and State 5 of New York, have invented certain new and useful Improvements in Roasting-Furnaces; and I do hereby declare the following to be a full, clear, and exact description of the invention, such as will enable others skilled in 10 the art to which it appertains to make and use the same.

My invention relates to improvements in furnaces for treating ores, and is primarily designed to treat refractory sulfid ores, more 15 especially those containing sulfids of iron, lead, silver and gold, although it is not restricted to such ores, as any ore, no matter how complex and refractory, can be successfully roasted in my apparatus and practically 20 all of the valuable constituents thereof separated from each other and saved.

My roasting furnace contemplates the use of heat, sulfur, oxygen and salt, as herein-after described, upon the ores and contemplates the production of chlorids of some of 25 the metals contained in the ore, and the volatilization of the chlorids so formed. The condensation, separation and recovery of 30 these chlorids is effected by suitable means, as set forth in an application of even date, Serial No. 271,470, the gold being recovered as the pure metal, the silver as solid chlorid of silver, the copper in solution as a chlorid or sulfate and the lead as solid sulfate of lead, 35 the last compounds named being easily reducible, producing the pure metals, silver, copper and lead.

It is well known that many chlorids can be quite easily volatilized by the proper amount 40 of heat and many attempts have been made to utilize this fact to recover metals from refractory ores, but, so far as I know, all these efforts have been either practical failures, when attempted to be carried out on a commercial scale, or else attended with so much expense as to be prohibited from use. One 45 reason for these failures, and the chief one, in my opinion, was the impossibility of obtaining suitable and economical methods and apparatus for condensing the volatilized fumes, but this point is carefully provided for in the companion application already referred to.

In the accompanying drawings:—Figure 1 50 is a side elevation of my improved furnace. Fig. 2 is an end view of the parts shown in

Fig. 1, looking from the left of this figure. Fig. 3 is a section of one of the furnace ends, and Fig. 4 is a cross section of one of the furnaces.

In a strong frame, preferably made of iron or steel, are mounted any desired number of furnaces *b*, *c*, *d*, and *e*, four being shown on the drawing. This frame is composed of upright end posts *a*, cross beams *f*, with corner braces *g* between said posts and beams, center posts *h*, and diagonal braces *i*, the whole forming a rigid structure in which the furnaces and other parts are located. In Fig. 2 inclined side bracing beams *j* are 70 shown on one side of the main frame and these may be used on both sides of said frame, if desired. The various pipes, hoppers, driving devices, &c., are supported in or on said frame or extensions thereof.

k represents a hopper into which the ground raw ore is fed. From the bottom of this hopper the ore is fed along by the spiral conveyer *m*, driven by a belt or sprocket chain passing over the pulley or wheel *n*, and then drops through the pipe *l* into the higher end of the upper inclined furnace, where it is roasted, the spiral conveyer, packed with fine ore, acting as a stop to prevent the gases from passing out through the hopper. The ore is 85 finely pulverized before it is fed into the hopper *k*, preferably so that it will pass through a 40 mesh sieve.

Each of the furnaces is composed of a shell *o*, made of iron or steel, composed of sections 90 bolted together, Fig. 4, and lined with a fire brick construction, alternate rows being the ordinary curved fire brick and the intermediate rows being nearly triangular in cross section, as shown at *p* in Fig. 4, which serve 95 as shelves to lift the ore from whence it is spilled down to the bottom of the furnace, thus insuring a thorough stirring of the ore. As will also be seen from Fig. 4, the inclined, or longer sides of these triangular 100 bricks *p*, form with the ends of the curved bricks small recesses. So that the said ends of the said curved bricks, constitute shelves of lesser dimensions, than do the bricks *p*. These recesses, serve as lodging places for 105 small quantities of fine particles of ore, and these lesser shelves lift the same, and finally discharge them, precisely as the larger shelves discharge their larger quantities. 110 By the use of my larger shelves at such frequent intervals, and also by the use of the combination of these two sets of shelves,

operating on different quantities of ore, I secure a much more thorough stirring of the same, than has been heretofore possible. In the furnace *b* the ore is roasted, to drive off the larger part of the sulfur, incidentally forming a small percentage of sulfates of some of the metals present. I do not attempt, however, to carry this roasting operation to a "dead roast", for in such a case, 10 it would be necessary to add more sulfur, as a small percentage of sulfur is needed to perfectly carry out my method.

To one end of the furnace *b* is attached a discharge pipe *q*, provided with a valve *r*, 15 which pipe leads into a pipe *s*, supported on the top of the main frame, which pipe leads away the sulfurous acid gas to a sulfuric acid plant (not shown) in which this gas is saved.

The furnaces *b*, *c*, *d*, *e* are similar in structure but are inclined in opposite directions, 20 Fig. 1, and located in opposite angles of the main frame, Fig. 3, and as they are all continuously revolved, the ore slowly travels from the hopper *k* back and forth through the furnaces until it is finally discharged through the pipe *t*, which is preferably provided with 25 a screw conveyer (not shown) or similar device, to prevent any of the volatilized materials from escaping therethrough and going 30 to waste, though this is not absolutely necessary. Each furnace is provided with a plurality of flanges *u*, Fig. 4, each of which rests in two grooved rollers *v*. Each furnace may be provided with the usual rack, with 35 which a gear wheel, such as *w*, engages, or it may be revolved by turning one of the rollers *v*. These rollers and wheels are all mounted on inclined shafts, such as *x*, to correspond with the inclination of the respective furnaces. Any suitable means for rotating 40 these furnaces may be used. I have shown, for the lower two furnaces *d* and *e*, a shaft *y*, mounted in one of the posts *h* and having a gear wheel *z*, which meshes with the gear 45 wheel 1, on the shaft which rotates the furnace *e*, a sprocket wheel 2, connected by a sprocket chain (not shown) with the sprocket wheel 3 on the driving shaft for the furnace *d*, and a sprocket wheel 4, which is driven by a 50 sprocket chain (not shown) from a point some distance from the main frame. The means shown for rotating the furnaces *b* and *c* are similar in structure. Into the upper end of the furnace *c* salt is delivered, by means of 55 the hopper 5, screw conveyer 6 and pipe 7, similar in structure to the corresponding parts already described. Instead, however, of using the furnace *b* as a roasting furnace, I may use it as a volatilizing furnace, if desired, like the furnaces *c*, *d*, and *e*, the roasting being done in a separate, detached furnace, in which case the ground and roasted ore, mixed with the proper percentage of salt, would be fed into the hopper *k* and the 60 hopper 5 dispensed with. From the dis-

charge end of the furnace *b* the roasted ore is delivered through the inclined pipe 8 into the receiving end of the furnace *c*, being mixed with salt, as it enters. In this furnace *c*, the formation of volatile chlorids begins and under the action of heat, sulfur, salt and oxygen (air being blown into the furnace, as hereinafter described) the reactions take place which eventually turn practically all the gold, silver, lead, and copper present 70 into chlorids, which are volatilized. Some small part of the lead and copper goes over into the condenser as sulfates and sulfurous and sulfuric acids are also formed in small quantities, all of which, together with the 75 volatile chlorids, go over into the condenser.

Any suitable means for heating the furnaces may be employed. For the sake of clearness, however, the heating means is not 80 shown.

Each of the furnaces is revoluble but the ends thereof are stationary, one of these ends (an inlet end) being shown in detail in Fig. 3. It consists of a metal cylinder 9, closed at one end and provided with a lining 10 of fire 90 brick or other refractory material. It is also provided with an inclined shelf 12, to conduct the ore, falling from the furnace next above it, well into the end of the furnace. A brace 13 holds this shelf firmly. The furnace does not touch the end or cap 9 but is separated from it by an annular space 11 and to prevent any volatile material from escaping through this space, instead of going over 95 into the condenser, a steady current of air 100 or oxygen is blown through this annular space, supplying the oxygen needed for the chemical reactions, preventing the volatile materials from escaping and going to waste and creating a slight air pressure in the furnace, which aids in forcing the volatilized material into the condenser. To effect these results an annular, flaring flange 14 is bolted onto the open end of the end or cap 9 and to this flange is bolted a curved annular piece 110 15, to which in turn is bolted the annular piece 16, the parts 15 and 16 being brought nearly together at their free edges, thus forming an annular tube provided with a narrow annular delivery slot, Fig. 3. The 115 part 16 is provided with an annular flange 17, which comes close to, but not in contact with, the shell of the furnace and with a shoulder 18 with which one edge of the piece 15 engages. The annular tube thus 120 formed is connected by a valved pipe 19 with a pressure pipe 20, one of these pipes being located near each end of the main frame, these pressure pipes being, respectively, connected by pipes 21 and 22 to a pipe 23 which 125 delivers compressed air to the apparatus.

From each end of each of the volatilizing furnaces *c*, *d*, and *e* leads a pipe, such as 24, provided with a valve, as 25, into a pipe, as 26 or 27, at either end of the furnaces. 130

(Many of the parts referred to throughout the specification being duplicated, one only of them has, as a usual thing, been described). The pipes 26 and 27 deliver the 5 volatile products into a pipe 28, which leads into a boiler, one end of which is shown at 65, Fig. 1. The volatile products are highly heated, often up to 1800° F or more, and this. heat is utilized to generate steam in the 10 boiler, which is used for any desired purpose, such as revolving the furnaces. This preliminary cooling, which, however, must not be allowed to proceed far enough to permit any of the volatilized products to be con- 15 densed in the boiler, also lightens the work of the condensing apparatus. After passing through the boiler the volatilized products are delivered into a condenser. Any desired form of condenser may be used, but I prefer 20 the form shown in the companion application of even date, Serial No. 271,469. Practically all of the lead, copper, silver and gold is saved in the condenser. If the ore contains zinc, this may be practically eliminated during 25 the roasting operation and the zinc recovered or thrown away, as circumstances dictate. If the ore contains iron, this will be discharged through the pipe *t* at the end of the lowest furnace *e*, either as fine metallic 30 iron or as a magnetic oxid, or a mixture of the two. Both of these can be readily separated from the gangue and waste by a magnetic separator, and the iron can then be recovered as metallic iron in the usual way. 35 Many ores, however, contain too small percentages of iron and zinc to warrant the saving of these metals, especially in localities where labor, fuel, etc., are high, as is the case in many sections where these complex refractory sulfid ores occur. The iron and zinc are 40 therefore saved or allowed to go to waste, as circumstances dictate.

I claim:—

1. In a furnace for the treatment of refractory ores, a rotary roasting furnace composed of a shell lined with refractory fire bricks, the alternate rows of said fire bricks being substantially triangular in cross section forming shelves and recesses for the ore, 45 substantially as described.

2. In a furnace for the treatment of refractory ores, a rotary roasting furnace composed of a shell lined with refractory fire bricks, the alternate rows of said fire bricks 50 being substantially triangular in cross section and forming shelves, substantially as described.

3. In an apparatus for the treatment of refractory ores, the combination of an inclined open-ended rotary furnace, means for supporting and rotating said furnace, a 55 stationary cap for each end of said furnace, said cap being provided with an inclined shelf and with feed and discharge pipes, and said

furnace being lined with fire brick, the alternate rows of which are approximately triangular in form and project farther toward the interior of the furnace than the intermediate rows forming shelves and recesses for the ore, and an annular air forcing 65 device carried by each of said caps, provided with a narrow slit directed into the open end of said cap, substantially as described.

4. In an apparatus for the treatment of refractory ores, the combination of a supporting frame, a plurality of inclined rotary furnaces carried by said frame, said furnace being inclined in opposite directions successively, whereby the ore may be easily passed from the higher end of the upper- 70 most furnace to the lower end of the lowermost furnace, said furnaces being mounted in a staggered position relatively to each other on said frame, a hopper provided with an air closure arranged to feed into the 75 upper end of the highest furnace, a hopper provided with an air closure connected to the upper end of the second furnace from the top, means for revolving said furnaces, and stationary caps for each end of each of 80 said furnaces, each cap being provided with means for forcing air thereinto, said furnace being lined with fire brick, the alternate rows of which are triangular and rectangular 85 in cross section, substantially as described. 90

5. In an apparatus for treating refractory ores, the combination of an inclined cylindrical furnace, means for rotating said furnace, and a cap for each end of said furnace provided one with an ore inlet, and the 100 other with an ore outlet; a gas outlet; an inclined shelf rigid with one of said caps adapted to direct the ore into said furnace and an annular air-forcing device provided with a slot directed into the open end of the 105 cap, each of said caps surrounding the corresponding open end of the furnace without touching it, substantially as described.

6. In an apparatus for treating refractory ores, the combination of an inclined rotary 110 furnace provided with open ends; of a stationary cap for each end of said furnace, one of which is provided with a feed pipe and an inclined shelf rigid therewith, and the other of which is provided with a discharge pipe and with an annular pipe rigid 115 therewith adapted to discharge air under pressure into said furnace, and each of said caps inclosing one end of said furnace but not in contact therewith, substantially as 120 described.

In testimony whereof, I affix my signature, in presence of two witnesses.

HASCAL A. HOGEL.
